SPECIFICATION forming part of Design No. 20,193, dated October 7, 1890.

Application filed September 6, 1890. Serial No. 364,175. Term of patent 3½ years.

To all whom it may concern:

Be it known that I, ARTHUR L. HALLIDAY, a subject of the Queen of Great Britain, residing at New York city, New York, have invented a new and original Design for Carpets, of which the following is a specification, reference being had to the accompanying photograph, which forms a part of the same.

The invention relates to a design to be worked into or upon surfaces, such as carpets or similar fabrics; and it consists in the novel configuration and grouping of figures herein specifically shown and claimed.

The accompanying photograph is a face view of a carpet showing my new design.

My design consists of two parts, the body A and the border B.

The body A contains large clusters of flower and leaf forms having scroll-shaped stems, and several large flower forms and clusters of flower and leaf forms. Several somewhat star-shaped flower forms are arranged in curved lines, passing around and among the flower and leaf forms.

The border B contains in its middle portion 25 large flower forms and clusters of flower and leaf forms and several somewhat star-shaped flower forms arranged in curved lines. The inner margin is composed of several small ornaments. The outer margin is composed of 30 somewhat crown-shaped figures mainly arranged in an undulating line. Within the outer margin are flower forms and smaller ornaments arranged in undulating lines.

What I claim, and desire to secure by Letters Patent, is—

1. The design for carpets, consisting of the body A, substantially as shown.
2. The design for carpets, consisting of the border B, substantially as shown. 40
3. The design for carpets, consisting of the body A and the border B, substantially as shown.
